The ornamental design for a curing oven for photopolymerization, as shown and described.

DESCRIPTION

FIG. 1 is a top plan view of a curing oven for photopolymerization showing our new design;

FIG. 2 is a bottom plan view;

FIG. 3 is a front elevational view;

FIG. 4 is a rear elevational view;

FIG. 5 is a right side elevational view;

FIG. 6 is a left side elevational view; and,

FIG. 7 is a perspective view thereof, shown with the door in any open position.

The broken line showing of a fragmented electrical cord is for illustrative purposes only and forms no part of the claimed design.
